UNITED STATES PATENT OFFICE.

FRANK E. BUTTERFIELD, OF ST. PAUL, MINNESOTA, ASSIGNOR OF ONE-HALF TO CARL SELCHERT, OF ST. PAUL, MINNESOTA.

WASHING-MACHINE CYLINDER.

Application filed September 16, 1925. Serial No. 56,679.

The present invention relates to a washing machine.

A desirable method of washing clothes, and one which produces a minimum of wear on clothes during a washing operation, is to force soapy water through the fabric of the clothes to soften and remove the dirt therefrom.

An object of the present invention is to form a rotatable cylinder for a washing machine with channels therein, to raise water in said channels above the normal water level in the machine, said water being carried back by gravity and driven through the fabric of clothes contained in the cylinder to clean them.

Another object of the invention is to form a washing machine cylinder with channels in the periphery thereof to carry water which will be forcibly driven through the clothes to clean them.

In order to attain these objects, there is provided, in accordance with one feature of the invention, a cylinder having a plurality of corrugations in the drum thereof, said corrugations being continuous throughout the circumference of the drum, the inward fold of each corrugation being provided with apertures therein for the admission therethrough of water to the interior of the drum, and the outer fold of each corrugation being continuous and substantially water tight throughout the entire circumference of the cylinder.

These and other features of the invention, not specifically mentioned, will be more fully brought out in the following description and the accompanying drawings, wherein:

Figure 1, is a view in side elevation of a washing machine of the rotating cylinder type, with a cylinder made in accordance with the present invention installed therein, a portion of the water compartment of the machine and a portion of the cylinder being broken away to show the construction thereof.

Figure 2, is a view in transverse section through the cylinder showing the construction thereof and the positioning of battens or lifts therein, the action of water therein during a washing operation being indicated by dotted lines; and

Figure 3, is an enlarged sectional view of a portion of a removable cover member po-

sitioned over the opening in the cylinder for the admission of clothes.

Referring to the drawings in detail, a washing machine A comprises a base portion 1 having a motor 2 mounted therein in the motor lane connected through shafts and gears in a well known manner to a drive mechanism 3. Since the drive mechanism of the machine illustrated is of a common type, and since various types of drive mechanisms may be employed without departing from the invention, it is unnecessary to describe the drive mechanism in detail. A clothes wringer 4 is pivotally mounted on top of a wringer drive mechanism 5.

A water compartment 6 is constructed of sheet metal and is provided with a cock 7 by means of which the water compartment may be drained.

A cylinder B is provided with discoid ends 8 which may be of sheet metal, the end shown in Figure 1 being provided with a stub shaft 9 fitted to the center thereof. The shaft 9 is supported for pivotal movement in a bearing 10, the other end of the cylinder being centrally pivotally supported with respect to the operative drive mechanism to be oscillated thereby.

A corrugated casing or drum 11 is integrally secured to the discoid end members 8 as by flanging at 12. The drum is provided with a plurality of circumferential corrugations 13 concentric with the discoid ends 8, the inner folds of the corrugations being preferably flattened as at 14 and provided with a plurality of holes 15 on the inner folds of said corrugations. The corrugations, for the purpose of the invention, are preferably fairly large, about six being employed in a cylinder approximately eighteen inches long. A plurality of battens or lifts 16 are secured to the interior face of the cylinder to extend longitudinally thereof, five of such lifts being illustrated in the present instance.

A cover 17 is provided, having corrugations therein to correspond to the corrugations in the cylinder, the cover extending the entire length of the cylinder. Affixed to each edge of the cover is a reinforcing and cover retaining member 18 which is integrally secured to the cover member as by spot welding to extend beyond the end thereof and supportingly rest on the edges of the

cylinder adjacent the cover opening. The cover fits into the cover opening to lie flush therewith on its inner side so as to provide uninterrupted channels throughout the entire circumference of the cylinder in each of the outward folds of the corrugations 13 therein.

In operation, a quantity of soapy water is poured into the container 6, and clothes not shown, are introduced into the cylinder through the cover opening. The cover 17 is then secured in position as by means of locking lugs 19 carried by the cylinder, and having locking engagement with the cover 15 to secure it in position during a washing operation. The cover is then locked in place to close the opening in the cylinder and the cylinder is then caused to oscillate by means of the motor 2 and the drive mechanism. 20 The cylinder is preferably rotated a predetermined number of revolutions in one direction and is then automatically reversed and rotated a predetermined number of revolutions in the opposite direction in accordance with a well known principle of 25 operation of cylinder type washing machines.

During a washing operation the water in the channels formed by the outer folds of 30 the corrugations 13 is forced, by the action of the lifts 16 and the friction between the water and said channels, to flow in the direction of rotation of the cylinder, and is carried by the channels above the normal 35 level of the water in the container. It then falls back by gravity, as shown in dotted lines in Figure 2 and sets up currents in the reverse direction to that of the rotation of the cylinder. These reverse currents, as

well as the normal currents previously mentioned, act to force the water through the clothes, which are also kept in an agitated condition by the rotation of the cylinder. After a washing operation is completed, the mechanism is stopped and the cover removed. The clothes may then be removed from the cylinder and the water drained from the container by means of the drain cock 7. In order to completely drain the cylinder it may be manually rotated to 50 bring the cover opening on the lower side of the cylinder to permit the water to flow out of the channels formed by the outer folds of the corrugations 13.

What I claim is:

1. A washing machine cylinder having discoid end members centrally supported for oscillation in a water container, a perforated wall connected to the peripheries of said end members, said wall having a plurality of unperforated continuous annular channels therein, and battens connected to the interior of the wall to bridge said channels. 60

2. A washing machine cylinder having a plurality of corrugations in the periphery thereof, said corrugations being continuous throughout the periphery of the cylinder to form channels encircling said cylinder, said corrugations being provided with apertures 70 in the inner folds thereof only, and a plurality of battens mounted transversely of the corrugations to bridge the channels formed thereby. 65

In testimony whereof I affix my signature. 75

FRANK E. BUTTERFIELD.
